(57) **CLAIM**

The ornamental design for a particulate material spreader, as shown and described.

DESCRIPTION

FIG. 1 is a left side view of the particulate material spreader showing our new design;

FIG. 2 is a front view thereof;

FIG. 3 is a top view thereof;

FIG. 4 is a perspective view thereof;

FIG. 5 is a front isometric view shown in stacked condition; and,

FIG. 6 is a rear isometric view thereof shown in stacked condition.

The features depicted by broken lines in FIGS. 5 and 6 are for illustrative purposes only and form no part of the claimed ornamental design.
